Des. 192,486
Patented Mar. 27, 1962

192,486

CONTAINER FOR PLANT ROOTS OR THE LIKE

Robert M. Lambert, 29 Dixie Drive, Raleigh, N.C.

Filed Apr. 12, 1961, Ser. No. 64,752

Term of patent 14 years

(Cl. D58—17)

FIG. 1 is a perspective view of a container for plant roots or the like showing my new design;

FIG. 2 is a top plan view;

FIG. 3 is a bottom plan view;

FIG. 4 is a sectional view taken on line 4—4 of FIG. 1; and

FIG. 5 is a sectional view taken on line 5—5 of FIG. 4.

The dominant features of the design are shown in full lines.

I claim:

The ornamental design for a container for plant roots or the like, as shown and described.
